Attorney

UNITED STATES PATENT OFFICE.

HARRISON R. GROSSMAN, OF PHILADELPHIA, PENNSYLVANIA.

FINGER-RING.

1,383,104.

Specification of Letters Patent. Patented June 28, 1921.

Application filed September 29, 1917. Serial No. 193,918.

To all whom it may concern:

Be it known that I, HARRISON R. GROSSMAN, a citizen of the United States, residing at Philadelphia, in the county of Philadelphia and State of Pennsylvania, have invented certain new and useful Improvements in Finger-Rings, of which the following is a specification.

The basic object of my invention is to provide a novel form of finger-ring removably carrying an identifying disk, and adapted, also, as a container for, say, a miniature photograph, medicines, anesthetics, etc.

A further object is to provide a finger-ring of this character which shall be absolutely water-tight and moisture-proof, as concerns the internal chamber thereof, whereby the contents thereof may be kept intact against the injurious effects of moisture, dirt, etc.

A further object is to provide a finger-ring of this character which may closely resemble an ordinary ring, the fact that it contains an internal chamber to which access may be had not being obvious to one not acquainted with the construction of the ring.

A further object is to provide a ring of this character which shall be slight and ornamental in appearance, and strong and durable in use.

A further object is to provide a finger-ring of the construction outlined which will be simple in construction and economical to manufacture, and which may be sold at a low price.

With these objects in view, and others appearing as the specification proceeds and the nature of the invention more fully develops, the invention resides in the novel construction, combination and arrangement of parts of a finger-ring, as will be herein-after fully described in the specification, summarized in the claims, and illustrated in the accompanying drawing.

In the drawing, which graphically portrays my invention, like reference-characters denote corresponding parts throughout the several views. The different figures or views of the drawing may be briefly described as follows:

Figure I is a perspective view of a finger-ring constructed in accordance with my invention;

Fig. II is a fragmentary top plan view

thereof, on an enlarged scale, the screw-cap being removed;

Fig. III is a sectional view, on the line 3—3, Fig. I; and

Fig. IV is a top plan view of an identifying disk carried within the ring.

Figs. V and VI are sectional views of two forms of the screw-cap constructed to detachably carry the identification-disk.

Referring, now, in detail to the drawing:

1 designates the body of the ring, which, as usual, is an annular band, to fit the finger of the wearer, and is provided with a head 2 having an annular, exteriorly screw-threaded flange 3 inclosing a chamber 4 having a preferably flat, imperforate bottom 5.

6 is an annular cap having a marginal, internally-threaded flange 7 adapted to engage the screw threads of the flange 3 of the ring. The exterior face of the cap may be suitably engraved, or otherwise decorated or ornamented, and the edge thereof may be knurled, as shown at 8, both to provide an ornamental appearance and to facilitate screwing the cap on the ring.

As shown in the drawing, the edge of the cap seats on the shoulder of the ring portion and this exterior surface 8 forms a substantially continuous wall with the exterior surface of the flange 3, whereby the joint between said ring portion and the cap is rendered inconspicuous.

The advantage of a screw cap connection is that it presents a strong and durable construction, and that the chamber 4 is water-tight and moisture-proof, so that the contents of the chamber may be kept intact, against the injurious effects of moisture, dirt, etc.

The chamber 4 contains an identification disk 9, which may be suitably inscribed with indicia identifying the wearer of the ring. As this ring is particularly adapted and intended for use by soldiers, the identification feature thereof is important, and makes the ring particularly useful. The ring is also adapted to carry, in the chamber 4 thereof, a photograph 10, or the like. It may also carry anesthetics and medicine, etc.

As shown in Fig. 5, the annular screw-cap 6' is provided, centrally, on its under surface, with a socket 6^a formed, as shown, with a curved side wall, so that the interior of said socket is wider than the mouth thereof. The identification-disk 9^a is formed of

spring metal, and is bent up, centrally, so as to form a hollow head 9^b of the shape of said socket, and adapted to spring into said socket when forcibly pushed through the mouth thereof. By this means, the identification-disk is yieldingly retained by the screw-cap.

As shown in Fig. 6, the screw-cap 6^{''} is provided, centrally, on its under surface, 10 with a screw-threaded socket 6^{aa}, into which is screwed the threaded stem 9^{bb} centrally carried by the identification-disk 9^{aa}. Thus, the identification-disk is detachably carried by the screw-cap.

Having thus fully described my invention, the many advantages thereof will be apparent, especially to those skilled in the art to which it pertains. It is understood, of course, that changes, especially in detail, 20 may be made in the physical embodiment

disclosed, within the terms of the appended claims, without departing from the spirit and substance of the invention, or necessarily sacrificing any of its advantages.

Having thus fully described my invention, 25 what I claim as new and desire to secure by Letters Patent of the United States is:

1. A finger-ring provided with a recess, a screw cover for the top of said recess, an identification-disk, and co-acting structural 30 means carried by said cover and disk for securing said disk to said cover.

2. A finger-ring provided with a recess, a cover for said recess provided with a threaded cavity, and an identification-disk provided with a threaded stem engaging said cavity.

In testimony whereof, I affix my signature.

HARRISON R. GROSSMAN.
